UNITED STATES PATENT OFFICE.

CLAUD L. COYLE, OF CLARENCE, MISSOURI.

DESIGN FOR A VANITY CASE.

Application filed March 14, 1927. Serial No. 21,144. Term of patent 7 years.

To all whom it may concern:

Be it known that I, CLAUD L. COYLE, a citizen of the United States of America, residing at the city of Clarence, county of Shelby, State of Missouri, have invented a new, original, and ornamental Design for a Vanity Case, of which the following is a specification, reference being had to the accompanying drawings, forming a part thereof.

In the drawings Figure 1 is a side view, and Figure 2 is a rear view of a vanity case embodying my new design.

I claim:

The ornamental design for a vanity case as shown.

CLAUD L. COYLE.
